Primary Examiner — Robert M. Spear*(74) Attorney, Agent, or Firm* — Birch, Stewart, Kolasch & Birch, LLP(57) **CLAIM**

The ornamental design for a wireless speaker, as shown and described.

DESCRIPTION

1. Wireless speaker
- 1.1 : Perspective
- 1.2 : Front
- 1.3 : Back
- 1.4 : Left
- 1.5 : Right
- 1.6 : Top
- 1.7 : Bottom
- 1.8 : Additional view

The broken lines indicate unclaimed portions of the article that form no part of the claimed design; reproduction 1.8 is additional view showing the inside of the front speaker of the subject design while the speaker cover is removed.

1 Claim, 8 Drawing Sheets(56)
